(57) **CLAIM**

The ornamental design for a label enlarger, substantially as shown and described.

DESCRIPTION

FIG. 1 is a front perspective view of a label enlarger showing my new design, the broken lines to the bracket and cable are for illustrative purposes only and form no part of the claimed design;

FIG. 2 is a rear elevation view thereof;

FIG. 3 is a left side elevation view of FIG. 2;

FIG. 4 is a right side elevation view thereof;

FIG. 5 is a top plan view thereof;

FIG. 6 is a bottom plan view thereof;

FIG. 7 is a front perspective view of the label enlarger shown in FIG. 1 in full lines, the broken lines to the bracket and cable are for illustrative purposes only and form no part of the claimed design; and,

FIG. 8 is a front perspective view of a second embodiment of a label enlarger showing my new design, the broken lines are for illustrative purposes only and form no part of the claimed design, the rear elevation view, the left side elevation view, the right side elevation view, the top plan view, the bottom plan view of the label enlarger are the same as FIGS. 2,3,4,5 and 6, the undisclosed rear of the cable is not part of the claimed design.
